Patented July 9, 1912

Fig. 1.

UNITED STATES PATENT OFFICE.

ALFRED C. STEWART, OF LOS ANGELES, CALIFORNIA.

CARBURETER.

1,032,307.

Specification of Letters Patent. Patented July 9, 1912.

Application filed July 31, 1911. Serial No. 641,654.

To all whom it may concern:

Be it known that I, ALFRED C. STEWART, a citizen of the United States, residing at Los Angeles, in the county of Los Angeles and State of California, have invented a new and useful Carbureter, of which the following is a specification.

The main object of the present invention is to provide a carbureter in which the means for controlling the fuel regulating valve are at the top of the carbureter in position for convenient manipulation.

Another object of the invention is to provide a carbureter in which the use of stuffing boxes or similar expedients for the fuel regulating means are dispensed with.

Other objects of the invention will appear hereinafter.

The accompanying drawings illustrate the invention, and referring thereto: Figure 1 is a vertical section of the carbureter. Fig. 2 is a vertical section on line x^2-x^2 in Fig. 1.

The carbureter comprises a casing formed with a carbureter chamber 1 in its upper portion and an oil chamber 2 in its lower portion, said oil chamber being formed in a bowl-shaped member 2' attached to the casing 1, and said casing being formed with a plate or flange 3, closing the top of the oil chamber. Between the plate or flange 3 and the carbureter chamber 1, the casing is provided with an air inlet chamber 4, open at one side to the outer air and communicating with the carbureter chamber through an opening in the bottom of the carbureter chamber, a valve seat 5 being provided at this opening for coöperation with the air valve. The carbureter chamber 1 is provided with a lateral extension 6, having an outlet opening 7 in its top, a throttle valve 8 being provided in said outlet opening, and means being provided at said opening for connection to the intake of an engine.

The air valve 10 is formed as a conical head on the upper end of a hollow valve stem 11, said stem being mounted to slide vertically in a tubular guide member 12 on the body or casing of the carbureter. A recess 9 is formed in the cone shaped valve member 10 for receiving the upper end of the tubular guide member when the valve is in closed position, the member 10 telescoping over the member 12 and protecting the tubular guide from dust and dirt. Said valve member 10 is formed with a shoulder 13 adapted to seat on the seat 5 to shut off

the air when the valve is in lowermost position and above said shoulder the valve member 10 is formed with a corrugated wall 14, providing an evaporating surface for the fuel. The valve stem 11 is formed with a central bore or chamber 16 communicating at its lower portion through a perforation 17 and channel 18 in the side of the valve stem, and a perforation 19 in the tubular guide 12, with the interior of the oil chamber 2, so that the oil from the oil chamber 2 may enter the chamber 16 within the valve stem. At its upper end this chamber 16 communicates with a recess or chamber 20 formed in a cup-shaped valve seat member 20 which screws into a recess in the upper portion of the valve member 10, said cup-shaped member 20 having an opening 22 in its bottom, through which fuel may flow into chamber 20' in the member 20. The fuel valve consists of a conical plug 23 tapering upwardly and extending within the valve opening 22 to open or close the same more or less, according to the position of the plug 23 and the elevation of the valve member 10. Said valve plug 23 is preferably hung loosely to enable it to accommodate itself to the opening 22, for example, by means of a pivot pin 24 extending through the valve plug 23 and supported in a stud 25 extending downwardly from a screw disk or closure plug 26 adapted to screw into a tapped opening 27 in the top of the carbureter chamber 1. The stud 25 is recessed as at 25' to receive the upper end of plug 23 which enters loosely therewith. By turning the plug 26 it may be raised or lowered to adjust the height of the valve plug 23. A pawl 34 is pressed by a spring 34' into engagement with notches 42 in the closure plug 26 to lock it in set position. Said opening is of sufficient size to enable the valve member 10 and its attached parts to be removed through said opening when the member 26 has been removed. To retain the pin 24 in place a sleeve 28 may be provided slidably mounted on the stud 25 and having an annular flange 29 surrounding said pin and normally holding the same from displacement, said sleeve being held down in position by a spring 30. The lower part of valve seat member 20 is reduced so as to form an annular space 31 between the members 20 and 10, this space connecting with the interior of member 20, through perforations 32 in member 20, and member 10 having radial passages 33 leading from space

31 to the carbureter chamber, these passages opening at the corrugated wall portions 14 of member 10.

The oil chamber member 2' may be secured to the body of the carbureter by an annular flange 33 on the bottom of the member 2', screwed on the lower end of the tubular member 12, a channel 36 being provided in this tubular member to allow oil to flow into the space 37 within this flange and below the valve stem to enable the valve stem guide to act as a dash pot.

Any suitable means may be provided for maintaining a definite level of oil in the oil chamber, said means consisting, for example, of a float 38 pivotally mounted at 39 within the chamber for controlling a valve 40 in the inlet passage or connection 41 for the fuel. Oil chamber 2 may be provided with a vent 43.

The operation is as follows: The oil being maintained at a definite level in the oil chamber, flows through the passages 19, 18 and 17 into the chamber 16 within the hollow valve stem, and when the throttle 8 is opened and the engine is in operation the suction from the engine produces a partial vacuum in the carbureting chamber 1, and causes the valve member 10 to be lifted. Opening communication from the air inlet past said valve member into the carbureter chamber and also causing the valve seat member 22 to move upwardly with respect to the upwardly tapering valve plug 23, thereby enlarging the opening between the fuel valve plug 23 and the valve seat member 22 in correspondence with the opening of the air valve. The suction from the mixing chamber 1 also causes the oil to rise in the chamber 16 of the valve member and to pass through the opening between the valve plug 23 and the valve seat member 22, and to flow into the chamber 20' in member 20 and out through the openings and passages 32, 31 and 33, the oil being discharged at the corrugated wall 14 in contact with the air in the carbureter chamber and directly adjacent to the incoming current of air as it passes through the opening 50 of the air valve. The valve plug 23 hangs in vertical position by gravity and adapts itself to any variations in the position of the valve seat member 22. In case it is desired to remove the air valve, it is only necessary to unscrew the closure member 26, remove said closure member with the valve 23 attached thereto and lift the valve member 10 with its stem out through the opening 27. The fuel supply may be regulated at any time by releasing the locking means 34 and turning the closure plug 26 to raise or lower the valve plug 23. If at any time it is desired to replace the valve plug 23, this may be conveniently done by removing the closure plug 26 along with the valve plug,

pushing up the sleeve 28 and removing the pin 24, and then inserting the new plug and replacing the pin and allowing the sleeve to swing back to normal position.

What I claim is:

1. In a carbureter, a casing provided with a carbureter chamber, an oil chamber below said carbureter chamber, an air inlet chamber between said oil chamber and carbureter chamber, said carbureter chamber having an opening in its bottom, communicating with the air inlet chamber, a vertically movable valve for closing said opening, said valve having a vertical hollow stem and provided with a valve seat at the upper portion of said stem, a tubular guide for said valve stem, said guide and valve stem being provided with passages establishing communication for oil from the oil chamber to the interior of the valve stem, an upwardly tapering valve plug extending through the said valve seat in the upper portion of the valve stem, and means in the top of the carbureter chamber for supporting said valve plug.

2. In a carbureter, a casing provided with a carbureter chamber, an oil chamber below said carbureter chamber, an air inlet chamber between said oil chamber and carbureter chamber, said carbureter chamber having an opening in its bottom, communicating with the air inlet chamber, a vertically movable valve for closing said opening, said valve having a vertical hollow stem and provided with a valve seat at the upper portion of said stem, a tubular guide for said valve stem, said guide and valve stem being provided with passages establishing communication for oil from the oil chamber to the interior of the valve stem, an upwardly tapering valve plug extending through the said valve seat in the upper portion of the valve stem, and means in the top of the carbureter chamber for supporting said valve plug, comprising a plug screwing into the top of the carbureter chamber and a loose connection between said closure plug and said valve plug to permit the valve plug to accommodate itself to said valve seat.

3. In a carbureter, a casing provided with a carbureter chamber, an oil chamber below said carbureter chamber, an air inlet chamber between said oil chamber and carbureter chamber, said carbureter chamber having an opening in its bottom, communicating with the air inlet chamber, a vertically movable valve for closing said opening, said valve having a vertical hollow stem and provided with a valve seat at the upper portion of said stem, a tubular guide for said valve stem, said guide and valve stem being provided with passages establishing communication for oil from the oil chamber to the interior of the valve stem, an upwardly tapering valve plug extending through the

- said valve seat in the upper portion of the valve stem, and means in the top of the carburetor chamber for supporting and adjusting said valve plug, comprising a closure plug screwing into the top of the carburetor chamber and connected to the valve plug to support the same, said closure plug being of greater diameter than said air valve.
- 10 4. In a carburetor, a casing provided with a carburetor chamber, an oil chamber below said carburetor chamber, an air inlet chamber between said oil chamber and carburetor chamber, said carburetor chamber having 15 an opening in its bottom, communicating with the air inlet chamber, a vertically movable valve for closing said opening, said valve having a vertical hollow stem and provided with a valve seat at the upper portion of said stem, a tubular guide for said valve stem, said guide and valve stem being 20 provided with passages establishing communication for oil from the oil chamber to the interior of the valve stem, an upwardly tapering valve plug extending 25 through the said valve seat in the upper portion of the valve stem, and means in the top of the carburetor chamber for supporting and adjusting said valve plug, comprising a screw plug screwing into the top 30 of the carburetor chamber and connected to said valve plug to support the same, and locking means engaging screw plug to lock the same in different angular positions.
- In testimony whereof, I have hereunto set my hand at Los Angeles, California, this 20th day of July, 1911.

ALFRED C. STEWART.
